UNITED STATES PATENT OFFICE

106,487

DESIGN FOR AN INSULATOR FOR AUTOMOBILE AERIAL

Roman Kopanski, Cleveland, Ohio, assignor to
The Ward Products Corporation, Cleveland,
Ohio

Application July 10, 1937, Serial No. 70,351

Term of patent 7 years

To all whom it may concern:

Be it known that I, Roman Kopanski, a citizen of the United States, residing at Cleveland, in the county of Cuyahoga and State of Ohio, have invented a new, original, and ornamental Design for an Insulator for Automobile Aerial, of which the following is a specification, reference being had to the accompanying drawing, forming part thereof.

In the drawing,

Fig. 1 is a front elevational view of an insulator for automobile aerial showing my new design.

Fig. 2 is a side elevational view thereof; and
Fig. 3 is a top plan view thereof.

I claim:

The ornamental design for an insulator for automobile aerial, as shown.

ROMAN KOPANSKI.
